UNITED STATES PATENT OFFICE

1,992,927

METHOD AND APPARATUS FOR RADIO BEACON COURSE AND QUADRANT IDENTIFICATION

Francis W. Dunmore, Washington, D. C., assignor to the Government of the United States, as represented by the Secretary of Commerce

Application February 4, 1933, Serial No. 655,190

10 Claims. (Cl. 250—11)

(Granted under the act of March 3, 1883, as amended April 30, 1928; 370 O. G. 757)

The invention described herein may be manufactured and used by or for the Government of the United States for governmental purposes only without the payment of any royalty thereon.

5 My invention relates to an improvement in the radio beacon of the visual, aural or combined visual and aural types in which a pilot when lost is given an identification signal which tells him which of the four quadrants he may be in or which of the four courses he may be on, or whether or not he has passed by the beacon station.

With the radio range system as now used, if a pilot should become lost due to some emergency which might divert his attention from the radio beacon course indications, especially when near the radio beacon, it becomes a very difficult matter for him to reorient himself, especially if he has passed the beacon in the meantime. His course indications may show him to be in one of two quadrants or on any one of four courses, he does not know which. Only by a process of assumption and a laborious method of flying over a considerable distance involving on the average an hour's time can he orient himself. A radio beacon should not only function to keep a pilot from getting lost but it should also provide means whereby in case he does become lost he may readily orient himself and get on a known course. This invention describes such a means, requiring but slight modifications at the radio beacon and no extra equipment on the airplane.

In one form of my invention, identification signals sent in different directions and differently coded are transmitted from the radio beacon. 35 In the case of the visual type of radio beacon these signals are received aurally without interruption to the beacon service, while with the aural beacon, the beacon service is interrupted for four or five seconds every two or three minutes. From 40 the relative intensities of the coded identification signals, the pilot may determine which of the four quadrants he is in or which of the four courses he is on. In another form of my invention the identification signals instead of being coded differently in the different directions are sent with different frequencies of modulation. Other uses for and advantages of my invention will be more clearly understood by reference to the following description and diagrammatic drawings:

50 In the drawings

Fig. 1 shows the cardioid transmissions for position identification using two cardioids sent in opposite directions and along the line of one of the transmission line type of antenna systems.

Fig. 2 shows the circuit arrangement for transmitting the two cardioids as shown in Fig. 1.

Fig. 3 shows another arrangement in which four cardioids are transmitted consecutively each along the direction of one of the TL antennas.

Fig. 4 shows a diagram of one form of apparatus which utilizes my method of transmitting the four cardioids as shown in Fig. 3.

Fig. 5 shows the circuit arrangement for the transmission of the four cardioids in directions other than along the line of direction of the transmission line type of antenna system.

In Fig. 1 which shows one form of my invention, 13 and 14 represent the usual figure-of-8 transmission characteristic for giving the visual or 15 aural type radio beacon courses 9—10—11— and 12. The transmission for producing these courses may preferably take place from the transmission line type of antenna system consisting of cage 20 antennas 1, 2, 3 and 4, and transmission lines 5, 6, 7 and 8. The said transmission line type of antenna 25 system was more fully described in the "Bureau of Standards Journal of Research", vol. 10, January 1933, which was also republished in the "Bureau of Standards Research Paper No. 513", entitled "The cause an elimination of night effect in radio range beacon reception" by Harry Diamond—see particularly under subtitle "V. Transmission-Line Antenna System" (pp. 23-33 of said research paper). By properly phasing the currents in antennas 1 and 3 the energy radiated may 30 be made to cancel in one direction and add in the other, giving a cardioid transmission characteristic 16. This is done by introducing the proper phasing sections in the proper place in the transmission lines feeding the vertical antennas. The 35 positions of these phasing sections in the transmission lines are altered by means of suitable relays, such alterations producing the cardioid signals and reversing the direction of their transmission. A code signal consisting of one dot is sent when this cardioid is transmitted. By a reversal of this phasing, the energy may be radiated in the opposite direction giving cardioid 15. A code signal of two dots is sent when this cardioid 40 is transmitted.

Referring to Fig. 1, during the transmissions of the dot and double dot cardioid position identification signals, the beacon course signals 13 and 14 are interrupted in the case of the aural 50 type beacon for a period of four seconds every two or three minutes and in the case of the visual system the interruption is only for the time interval of each quick dot and as the dots are of very short duration, the interruption is 55

hardly perceptible on the pointer type course indicator with proper damping and filtering, and not objectionable in the case of the reed indicator. Every two or three minutes the reeds 5 will both drop in amplitude about $\frac{1}{2}$, for the instant the dot and two dots are being sent.

The pilot uses the system as follows: Referring to Fig. 1 a pilot may be lost on any course 9, 10, 11 or 12, or in an A (65 cycle) or N (86 $\frac{2}{3}$ cycle) 10 quadrant. He would locate himself as follows:

1. From the course signals he gets a strong N or 86 $\frac{2}{3}$ cycle signal. From this he knows he is in a region north or south of the beacon and not east or west of it, where he would obtain a 15 strong A or 65-cycle signal. Next, when the identification cardioid signal is heard he gets two dots noticeably louder than the one dot in the ratio of OQ to OP, showing him he is in the N or 86 $\frac{2}{3}$ quadrant north of the beacon and 20 not in the similar quadrant south of the beacon.

2. An on course indication is obtained from the beacon signal. Which of the four courses is the pilot on? When the position signal is heard, the two dots are very loud and the one dot hardly 25 audible. The pilot must therefore be on course 10. If he had heard the one dot loud and the two dots very weakly, he would have been on course 12. Had the one and two dots been of the same or nearly same intensity, he would have 30 been on course 9 or 11. To determine which of these he is on, he gets his compass heading when flying on the course and notes that it is in a southeasterly direction. He deviates off course to the right and obtains a pronounced N or 86 $\frac{2}{3}$ 35 cycle signal. He must therefore be flying southeast on course 11 since if he was on course 9 and flying southeast and deviated to the right, he would obtain a pronounced A or 65 cycle signal.

40 Even when lost in an A (65 cycle) or N (86 $\frac{2}{3}$ cycle) quadrant, the pilot can tell which of the two adjacent courses he is nearest by the relative strength of the dot and two dot signals. For example, if a pilot getting a strong A or 45 65 cycle signal hears the one dot about twice as loud as the two dots, in the ratio of OT to OR, this shows him he is somewhere in the region of the line ON near course nine and not in the region of the line OL near course twelve 50 along which line he would have heard the one dot very loudly and the two dots very weak in the ratio of OV to OU.

Another advantage of this invention is that the pilot may determine that he has passed over 55 the beacon when flying along courses 10 or 12 since the one dot changes to two dots when the beacon is passed in flying from course 12 to 10, and the two dots change to one dot when the beacon is passed when flying from course 10 60 to 12.

In Fig. 2 is diagrammatically shown an apparatus which utilizes my method for transmitting the two cardioids shown in Fig. 1. 17 is a motor driving the one dot sending disc 18 and 2 dot 65 disc 19. 20 and 21 are contacts for making the dots, 22 is a timing switch for sending the cardioids as often as desired. 23 is a double-pole double-throw relay operated by contacts 20 and 21 and serves to take the 65-cycle-86 $\frac{2}{3}$ -cycle 70 modulation off of a transformer 24 supplying the beacon amplifiers and puts on 1,000 cycle during the time of the cardioid transmissions.

The transformer 24 is of the standard type and serves to modulate the outputs of the two 75 amplifier legs in the radio beacon transmitter,

one leg supplying radio frequency power modulated at 65 cycle and the other radio frequency power of the same radio frequency but modulated at 86 $\frac{2}{3}$ cycles, both supplies of power entering the antennas through coils 43 and 44 and their attached transmission lines. 25, 26, 27 and 28 are the vertical antennas of the transmission line type of antenna system. These correspond to antennas 1, 2, 3 and 4 respectively, in Fig. 1. 39, 40, 41 and 42 are the coupling units to 10 antennas 25, 26, 27 and 28 respectively. 29, 30, 31 and 32 are phasing sections in the transmission lines for producing the figure-of-8 transmission for the beacon course signals. 33-34 and 35-36 are parts of 29 and 31, respectively, 15 which are thrown into the transmission line feeding antenna 25 or the transmission line feeding antenna 27 by means of open-circuit type double-pole single-throw relays 37 and 38. 37 and 38 are for producing the cardioid transmissions. 20 43 is a secondary supplying power to antennas 26 and 28 from a source of radio frequency 43a; and 44 supplies antennas 25 and 27 from a source of radio frequency 44a. 43 and 44 are coupled to the beacon transmitter output through a suitable goniometer. 45 is a single-pole single-throw relay which short-circuits coil 43 rendering antennas 26 and 28 inoperative during the cardioid transmissions from antennas 25 and 27.

With contacts 20 and 21 open, relay 23 is closed 30 on the back contacts putting 65 and 86 $\frac{2}{3}$ cycle modulation on the beacon amplifiers. Relays 37, 38 and 45 are open and relay 46 is closed. When contact 20 closes, relay 23 closes to the right putting 1000 cycle on the modulating amplifiers, relay 45 closes preventing any radiation from antennas 26 and 28, relay 46 opens taking the radio-frequency power supply from the center of the transmission lines supplying antennas 25 and 27, and relay 37 closes connecting secondary 44 to the opposite side of phasing coils 33 and 34 thus sending a dot cardioid transmission characteristic in the direction of antenna 25. When contact 21 closes, relays 23, 46 and 45 operate as before but relay 38 closes in place 45 of relay 37, thus sending a 2-dot cardioid transmission in the opposite direction. Relay 45 serves to render antennas 26 and 28 inoperative during the cardioid transmission from antennas 25 and 27.

Fig. 3 shows a further application of my invention in which the cardioid transmissions take place in four different directions instead of two. In this case, the cardioid transmissions take place along the direction of each antenna of the transmission line type of antenna system, regardless of their orientation in space and the position of the beacon courses. The system is merely an extension of that shown in Fig. 1, two more cardioid transmissions consisting of 3 and 4-dot signals 60 taking place at right angles to the two shown in Fig. 1.

In Fig. 3: 1, 2, 3 and 4 represent the location of the vertical antennas of the transmission line type of system. 47, 48, 49 and 50 represent the radio beacon courses. 51 represents the cardioid transmissions in the direction of antenna 1; 52 represents the cardioid transmissions in the direction of antenna 3; 53 represents the cardioid transmissions in the direction of antenna 2, and 54 represents the cardioid transmissions in the direction of antenna 4.

Fig. 4 is a circuit for sending the dot and 2-dot cardioid signals as shown in Fig. 2 and, in addition, the 3 and 4-dot cardioid signals, thus 75

producing the four cardioids shown in Fig. 3. In the circuit, 17 is a motor for driving a dot coding wheel 48; 47 is a slip ring for making contact with segments 53, 54, 55 and 56; 49, 50, 51 and 52 are brushes making contact with segments 56, 55, 54 and 53, respectively. 57 is the dot making contactor. 23 is a double-pole, double-throw relay connecting either the 65 cycle and 86% cycle modulation or the 1000 cycle to the beacon amplifiers through transformer 24. 25, 26, 27 and 28 are the vertical antennas of the transmission line type of antenna system. 29, 30, 31 and 32 are the phasing sections in the transmission lines. 37, 60, 38 and 63 are open-circuit double-pole, single-throw relays for changing the electrical position of radio-frequency supply to the transmission lines when sending the cardioid signals. 65 and 46 are closed circuit double-pole, single-throw relays for disconnecting the radio-frequency supply from the center of the transmission line when sending the cardioids, and 64 and 45 are single-pole, single-throw shorting relays for rendering the antennas inoperative in the set of antennas not transmitting cardioids during a given set of dot transmissions. 33, 34, 58, 59, 35, 36, 61 and 62 are sections of the phasing sections which are thrown into different parts of the transmission lines by relays 37, 60, 38 and 63 when sending the cardioids. 43 and 44 are the secondaries supplying the radio-frequency to antennas 26-28 and 25-27, respectively, from sources of energy 43a and 44a, respectively. This system operates similar to that described under Fig. 2 except that brushes 49, 50, 51 and 52 select the proper set of relays for sending the cardioids in the four different directions. When brush 49 comes in contact with segment 56, 57 closes, sending a 1-dot cardioid as previously described, in the direction of antenna 25. When 50 touches 55 and 57 closes twice, sending a two-dot cardioid in the direction of antenna 27. When 51 touches 54 and 57 closes, a three-dot cardioid is sent in the direction of antenna 26 and when 52 touches 53 and 57 closes four times making a four-dot cardioid in the direction of antenna 23. Contact wheel 22 serves to send the set of cardioid signals as often as desired.

In cases where it is necessary to send cardioid transmissions in directions other than along the line of the transmission-line type of antenna systems, it is necessary to simultaneously radiate two cardioid signals of the proper phase and amplitude from both antenna systems giving a resultant at an angle to the line of direction of the transmission line type of antenna system. A method of accomplishing this is shown in Fig. 5. This differs from Fig. 4 only in that contact wheel 66 has a different arrangement of segments so that when 57 closes to make one dot, 49 and 50 touch segment 70 operating both relays 37 and 60, as well as 23, 65 and 46, producing a resultant cardioid in a direction at, say, 45 degrees to antennas 25 and 26. When 57 closes to make 2 dots and 50 and 51 touch 69, relays 60 and 38 operate as well as 23, 65 and 46, producing a resultant cardioid at, say, 45 degrees to antennas 26 and 27. When 47 closes to make 3 dots and 51 and 52 touch 68, relays 38 and 63 operate as well as relays 23, 65 and 46, producing a resultant cardioid at, say, 45 degrees to antennas 27 and 28. When 57 closes to make 4 dots and 49 and 52 touch 67, relays 63 and 37 operate as well as relays 23, 65 and 46, producing a resultant cardioid at, say, 45 degrees to antennas 28 and 25.

A further application of my invention is that it enables a pilot to determine when he has passed over the beacon, which is of considerable help as it gives him a definite "fix". Referring to Fig. 3, assume a pilot to be flying northeast along course 47. He hears 1 dot very loudly and 2 dots very weak until he passes over the beacon on to course 49 then the 1 dot becomes weak and the 2 dots loud, indicating to him that he has passed over the beacon. This is the case with any one of the 4 courses. For example, when flying south on course 48, 3 dots will be heard very loudly until the beacon is passed, and then 4 dots will be heard very loudly on course 50.

It is understood that while the transmission line type of beacon antenna system has been shown this invention is not limited in its application to that type, but any form of antenna system may be used producing beacon courses of the aural or visual type in fixed directions, the unidirectional transmissions for the quadrant or course identification being obtained either from the beacon antenna system alone or this antenna system in combination with other suitable antenna systems. The crossed-loop beacon antennas in combination with a vertical antenna is an example of another workable combination. In this case the relays would function to tune and excite the vertical antenna with a radio frequency signal of proper phase and amplitude when sending the cardioids.

It is also understood that this invention is not limited to the transmission of the identification signals during an interruption of the beacon course signals in the case of the visual type beacon giving courses of the double modulation signal type, as such unidirectional identification transmissions may take place simultaneously on the same radio frequency with the beacon signal transmissions, from a separate antenna system, an audio-filter system being used on the receiver output to keep the identification signals from the visual course indicator. An advantage of this method is that the unidirectional identification transmissions could be sent continuously, the frequency of transmission being such as to require no wait on the pilot's part. This is an advantage, especially when using the signal to determine when the beacon has been passed over.

It is further understood that while aural reception of the unidirectional identification signals has been mentioned, the reception of these signals may be on a visual form of indicator if desired.

It is further understood that while mention has been made of sending a different coded signal in each of the different directions, that this invention is not limited to such a coded signal but may include the same signal in all directions of transmission but on a different frequency of modulation. In this case, referring to Fig. 4, relay 23 would be replaced by 4 relays each in series respectively with relays 37, 60, 38, 63, each relay connecting a different audio frequency on transformer 24. The 2, 3 and 4 dots on code wheel 48 would each be replaced by a single dot or dash.

While I have described and illustrated different examples of my invention, I do not wish to be limited to these specific examples since modifications may be made both in the circuits and apparatus within the scope of my invention.

What I claim is:

1. A radio beacon comprising means for transmitting range course signals in definite directions, means for interrupting the beacon course

- signal at suitable intervals, means for transmitting during the complete interval of interruption a series of unidirectional transmissions in different directions each of said transmissions being differently coded. 5
2. A radio beacon comprising means for transmitting beacon course signals and a series of unidirectional signals in definite directions, means for interrupting the beacon course signal at suitable time intervals and permitting the transmission during said intervals of interruption of the series of unidirectional transmissions in different directions from said radio beacon, each of said transmissions being differently coded. 10
3. A radio beacon, comprising means for transmitting range course signals of the double modulation visual type providing fixed course signals at definite angles, means for transmitting differently coded unidirectional signals at definite angles, four vertical antennas arranged in substantially opposing pairs for radiating said signals, each antenna being energized from said transmission means through a transmission line, 20
- 25 a plurality of two position relays connected to phasing sections in the said transmission lines and to the said means for transmitting range course signals and said means for transmitting the differently coded unidirectional signals, and
- 30 automatic code means operating said relays for producing the said fixed courses when in one of said positions and the said differently coded unidirectional signals when in the second of said positions. 35
- 35 4. A radio beacon of the double modulation type comprising means for transmitting range course signals at definite angles and including an antenna array having four vertical antennas arranged in substantially opposing pairs, non-radiating transmission lines supplying diagonally opposite antennas, sources of radio frequencies, one for supplying one of the transmission lines of diagonally opposite antennas, relays for connecting said source of radio frequency with said 40
- 45 transmission lines and to change the phase of the currents in the antennas, and another relay for changing the modulation of the current in said transmission lines, and a code signal means electrically connected with said relays for operating the same whereby certain of the loading sections in the transmission lines are connected in one position of the relay and disconnected with other loading sections in one position of the relays, said relays being so arranged that 50
- 55 the loading sections, when in said transmission line, are sufficient to produce a unidirectional transmission from a given set of said two antennas.
5. A radio beacon of the aural type comprising means for transmitting range course signals in 60
- 60 definite directions, means for interrupting at suitable intervals the beacon signals producing said courses, means for transmitting from the beacon antenna system during said interruptions a series of unidirectional radio transmissions in different directions, each of said transmissions being differently coded such that they may be differentiated. 65
6. A radio beacon of the double modulation type comprising means for transmitting range course signals on a given carrier frequency and means for transmitting on the same carrier frequency, but different modulation, unidirectional signals at definite angles, an antenna system for the transmission of said course signals, a second antenna system radiating the unidirectional transmissions in different directions, said unidirectional transmissions being differently coded in each of said different directions and transmitted simultaneously with said course signals. 5
7. A radio beacon of the visual type comprising means for transmitting range course signals in definite directions, means for radiating from the beacon antenna system a series of unidirectional radio transmissions in different directions, and modulated at a different audio frequency in each of said different directions, and means for interrupting the range course signals only for the period of each of said unidirectional transmissions. 10
8. A radio beacon of the aural type comprising means for range course signals in definite directions, means for radiating from the beacon antenna system a series of unidirectional radio transmissions in different directions, and modulated at a different audio frequency in each of said different directions, and means for interrupting the beacon course signals for the period of said unidirectional transmission. 15
9. A radio beacon of the double modulation type comprising means for producing fixed range course signals at definite angles and including 25
- 25 an antenna array having four vertical antennas arranged at the corners of a square, non-radiating transmission lines supplying each diagonally opposed antenna with the said beacon course signals, means for producing unidirectional signals 30
- 35 including a circuit and a 1, 2, 3 and 4-dot code wheel and contactor therefor in said circuit, two-position relays in said circuit and operated by said code wheel, said relays connecting certain loading sections in said transmission lines in 40
- 45 one of said positions and disconnecting certain other said loading sections in their second said position, said loading sections when in said transmission lines being sufficient to produce the unidirectional code signal transmission in different 50
- 50 directions from a given set of two of said antennas and each coded with a different number of dots in each of said different directions. 55
10. A radio beacon of the visual type comprising an antenna system, means for radiating from said antenna fixed double modulation range course signals in definite directions on a given carrier frequency; and means for radiating simultaneously from said antenna system, on the same carrier wave but on different modulation, unidirectional signals at definite angles and differently coded in different directions, respectively. 60
